W. A. MORRISON

SAFETY DEVICE FOR OIL INJECTION ENGINES

Filed Aug. 18, 1927

6 FIG.-1.

e FIG.-2.

INVENTOR.
William A. Morrison
BY *Herb C. Ogden*
HIS ATTORNEY.

UNITED STATES PATENT OFFICE.

WILLIAM A. MORRISON, OF EASTON, PENNSYLVANIA, ASSIGNOR TO INGERSOLL-RAND COMPANY, OF JERSEY CITY, NEW JERSEY, A CORPORATION OF NEW JERSEY.

SAFETY DEVICE FOR OIL-INJECTION ENGINES.

Application filed August 18, 1927. Serial No. 213,961.

This invention relates to fuel injection engines, but more particularly to a safety device adapted to be interposed in the fuel line of engines of this type.

5 One object of the invention is to automatically cut off the fuel supply to the engine whenever the pressure in the lubricating supply falls to a certain predetermined value.

Other objects will be in part obvious and 10 in part pointed out hereinafter.

In the drawings illustrating the invention and a practical application thereof,

15 Figure 1 is a side elevation of a fuel injection engine equipped with a device constructed in accordance with the practice of the invention, and

20 Figure 2 is an enlarged sectional view of the safety device showing the valve in position to permit the passage of fuel through the device to the engine.

Referring to the drawings, A designates generally an engine of the injection type having in this instance three cylinders B mounted on a base C. D is a fuel supply 25 tank from which leads a supply pipe E for conveying fuel to an oil filter box F mounted on the base C. The safety device G in this instance is attached to the oil filter box F and communicates with a fuel pump H and 30 through a pipe J.

From the fuel pump H the fuel is conveyed through a pipe K to a distributor L whereby it is distributed to the various cylinders B through pipes O.

35 Suitable means are provided for starting the engine A under the influence of pressure fluid, such as compressed air. These means in the present instance comprise a compressor P communicating with a receiver tank Q

40 through a discharge pipe R. In the construction shown, an air starting manifold S is mounted on the base C and communicates with the receiver tank Q through a pipe T and with the cylinders B through pipes U.

45 The manifold S may be provided with a suitable valve (not shown), but the position of which is indicated by a lever V whereby the valve may be manipulated for admitting the pressure fluid into the cylinders to set the 50 engine in operation.

In accordance with the present invention the device G comprises a casing W having a pair of chambers X and Y which communicate with each other through a bore Z in a 55 wall b between said chambers. The chamber

Y constitutes an inlet chamber and communicates with the fuel filter through a connection c carrying at its outer end a flange d through which may extend bolts e whereby the casing W may be attached to the filter 60 box F. Preferably, at the upper end of the chamber X is formed a connection f through which the fuel may pass to the fuel pump through the pipe J whereto the connection f is attached by means of bolts e.

65 At the entrance end of the bore Z is formed a valve seat g to cooperate with a valve h for controlling the admission of fuel from the chamber Y to the chamber X. The valve h in this instance is provided with a 70 plurality of wings j which cooperate slidably with the bore C for guiding the valve and above the wings j is formed a flange j' to which is attached one end of a corrugated collapsible diaphragm k, the other end of 75 the diaphragm k in this instance being secured to a cover o which forms a closure for the chamber X.

80 The ends of the diaphragm k may be suitably secured to the flange j' and the cover o to prevent leakage of lubricant under pressure from the diaphragm, such lubricant being conveyed thereto through a pipe p leading from a lubricating pump q whereby lubricant under pressure is forced to the various relatively movable surfaces of the engine.

85 In order to insure prompt closing of the valve h whenever the pressure of the lubricant in the diaphragm k drops to a value at which it is considered unsafe to continue the operation of the engine, a spring r is disposed beneath the valve h and is seated with its lowermost end on a spring seat s in a head t located at the lowermost end of the 90 casing W. The spring r is guided by a stem u carried by the valve h and is encircled by a corrugated collapsible diaphragm v secured at one end to the valve h and at its other end to the head t to seal the chamber 95 Y. The spring seat s in this instance is threaded into the head t and is provided with a bore w to receive slidably a piston rod x threaded at its upper end into the stem u.

100 Attached to the lowermost end of the piston rod x is a piston y which may consist of a cup leather z slidable in a cylinder 2 preferably formed integrally with the head t. In order to reinforce the cup leather z, a washer 105 3 is disposed therebeneath and a piston nut 110

4 may be disposed inside of the cup leather z for a similar purpose. The piston assembly in this instance is held on the rod x by means of the nut 5.

- 5 Pressure fluid for actuating the piston y is conveyed to the cylinder 2 through a pipe 6 connected at its opposite end to the air starting manifold S in such a manner that whenever the pressure fluid is admitted 10 into the cylinders B, communication between the pressure fluid supply and the cylinder 2 will also be opened for actuating the piston y , and thus opening the valve h .

The operation of the device, briefly described, is as follows: Let it be assumed that the valve h is in the closed position, which it will occupy while the engine A is idle or during the absence of lubricant under pressure in the diaphragm k . If then, the 20 lever V of the air starting manifold S be manipulated to admit pressure fluid into the cylinders B for starting the engine, a portion of pressure fluid will pass from the manifold S through the pipe 6 into the cylinder 2 and acting against the piston y will open the valve h simultaneously with the admission of pressure fluid into the engine A. It will thus be apparent that with the valve 25 in the open position an immediate supply of fuel will be available for the requirements of the engine.

Prior to the time that combustion takes place in the engine, the piston y will be exposed to pressure fluid under full line pressure and will thus be held open by the force 30 of the spring r . However, after combustion takes place in the cylinders B, communication between the air starting manifold and the engine will be cut off as will also that 35 between the manifold S and the cylinder 2, thus trapping a certain amount of pressure fluid in the cylinder 2 to hold the valve h open until the engine approaches its rated speed.

40 45 Immediately upon cutting off the supply of pressure fluid to the cylinder 2, the entrapped pressure fluid may leak from the cylinder 2 along the rod x into the diaphragm v and thence to the atmosphere, it being understood that the bore w in the 50 spring seat s is sufficiently larger than the rod c to permit of such leakage.

While the leakage of pressure fluid hereinbefore referred to is taking place, the 55 engine A will of course be accelerating thus raising the pressure of the oil in the lubricating system to a value which, when acting against the end of the flange j' of the valve, will maintain the valve h in the open position 60 and will continue to hold it thus as long as such pressure in the lubricating system exceeds that exerted by the spring r , and which pressure of course is one which it is considered essential to maintain in the 65 lubricating system. If, however, as some-

times happens, the pressure in the lubricating system, and consequently in the diaphragm k , drops to a value at which it is considered unsafe to continue the operation of the engine A, the spring r will advance the 70 valve h towards the seat g and as said valve approaches its seat, the suction created by the fuel flowing over the edge of the valve h through the bore Z will augment the force of the spring r and assist in closing the valve 75 h . In this way the supply of fuel to the engine will be cut off, thus stopping the operation of the engine and preventing any damage thereto due to lack of lubricant.

I claim:

1. In combination with an oil injection engine having a fuel supply pipe and a pressure lubricating system, a casing adapted to be interposed in the supply pipe, a valve in the casing controlling the flow of fuel through the casing and exposed to the pressure of said lubricating system for opening the valve, means forming a flexible connection between the lubricating system and the valve, a spring tending to close the valve, and pressure responsive means for holding the valve open until the value of the pressure in the lubricating system exceeds the force of the spring.

2. In combination with an oil injection engine having a fuel supply pipe and a pressure lubricating system, a casing adapted to be interposed in the supply pipe, a valve in the casing controlling the flow of fuel through the casing and exposed to the pressure of said lubricating system for opening the valve, a corrugated diaphragm forming a flexible connection between the lubricating system and the valve, a spring for closing the valve whenever the pressure in the lubricating system drops to a certain predetermined value, a spring seat threaded in the casing for adjusting the tension of the spring, a cylinder, a piston in the cylinder connected to the valve, and a pipe connecting the cylinder with a source of pressure fluid supply to actuate the piston for opening the valve and hold said valve open until the value of the pressure in the lubricating system exceeds the force of the spring.

3. In combination with an oil injection engine having a fuel supply pipe and a pressure lubricating system, a casing adapted to be interposed in the supply pipe, a valve in the casing controlling the flow of fuel through the casing and exposed to the pressure of said lubricating system for opening the valve, a corrugated diaphragm forming a flexible connection between the lubricating system and the valve, a spring for closing the valve whenever the pressure in the lubricating system drops to a certain predetermined value, a spring seat threaded in the casing for adjusting the tension of the spring, a cylinder beneath the casing, a pis-

ton in the cylinder, a rod connecting the piston to the valve, said rod being slidable through the spring seat, and a pipe connecting the cylinder with a source of pressure fluid supply to actuate the piston for opening the valve and holding said valve open until the pressure in the lubricating

system exceeds the force of the spring and the suction of the fuel flowing over the edge of the valve.

10

In testimony whereof I have signed this specification.

WILLIAM A. MORRISON.
